US00D952156S

(12) **United States Design Patent** (10) **Patent No.:** **US D952,156 S**
(45) **Date of Patent:** **** May 17, 2022**

(54) **BRACKET WITH CLIPS**

- (71) Applicant: **Edwards Lifesciences Corporation**,
Irvine, CA (US)
- (72) Inventors: **Andrew Nguyen Hoan**, Irvine, CA
(US); **Mandana Farhadieh**, Tustin, CA
(US); **Brian Patrick Murphy**, Costa
Mesa, CA (US)
- (73) Assignee: **Edwards Lifesciences Corporation**,
Irvine, CA (US)
- (**) Term: **15 Years**
- (21) Appl. No.: **29/665,012**
- (22) Filed: **Sep. 28, 2018**

Related U.S. Application Data

- (63) Continuation of application No. 15/801,009, filed on
Nov. 1, 2017, now abandoned.
- (51) **LOC (13) Cl.** **24-02**
- (52) **U.S. Cl.**
USPC **D24/169**

CLAIM

The ornamental design for a bracket with clips, as shown
and described.

DESCRIPTION

FIG. 1 is a bottom right perspective view of the design.

FIG. 2 is a front view thereof.

FIG. 3 is a back view thereof.

FIG. 4 is a right side view thereof.

FIG. 5 is a left side view thereof; and,

FIG. 6 is a top plan view thereof.

1 Claim, 4 Drawing Sheets
